UNITED STATES PATENT OFFICE.

WILLIAM T. HANEY, OF CHILDERSBURG, ALABAMA.

BOILER-CLEANER.

SPECIFICATION forming part of Letters Patent No. 398,612, dated February 26, 1889.

Application filed June 4, 1888. Serial No. 275,945. (No model.)

To all whom it may concern:

Be it known that I, WILLIAM TROUSDALE HANEY, of Childersburg, in the county of Talladega and State of Alabama, have invented a new and improved Boiler-Cleaner, of which the following is a full, clear, and exact description.

The object of the invention is to provide a new and improved boiler-cleaner, which is simple and durable in construction and effective in operation, serving to prevent sediment or crust from forming in the bottom of the boiler.

The invention consists of certain parts and details and combination of the same, as will be fully described hereinafter, and then pointed out in the claims.

Reference is to be had to the accompanying drawings, forming a part of this specification, in which similar letters of reference indicate corresponding parts in both the figures.

Figure 1 is a longitudinal sectional elevation of the improvement on the line $x-x$ of Fig. 2, and Fig. 2 is a transverse section of the same on the line $y-y$ of Fig. 1.

The improved boiler-cleaner consists of a brush, A, formed to correspond to the shape of the shell of the boiler B, as shown in Fig. 2. The brush A is preferably made of steel bristles secured to a block, C, having its top beveled, as shown in Fig 1, and the said block C is secured to one end of a rod, D, passing through a stuffing-box, E, formed in the head of the boiler B, said rod D being provided on its outer end with a handle, F, for conveniently moving the said rod D forward or backward in the boiler B.

The stuffing-box E is so located that a forward-and-backward movement of the rod D holds the same parallel with the shell of the

boiler, so that the brush A is held in contact with the interior surface of the boiler-shell when the said rod D is moved forward and backward.

The pressure of the water on the inclined back of the block C causes the latter to press the bristles of the brush A firmly against the inner surface of the boiler-shell, so that when the operator takes hold of the handle F and moves the rod D forward and backward said bristles of the brush A scrub on the surface of the shell of the boiler B, whereby all sediment or crust is prevented from forming on the lower part of the boiler B. This forward-and-backward movement of the brush A also agitates the water in the boiler, and hence prevents the sediment contained in the water from settling in the bottom of the boiler.

It will be seen that the device is always ready to be used, being a fixed part of the boiler, and it may be operated while the boiler is being used.

Having thus fully described my invention, I claim as new and desire to secure by Letters Patent—

1. In a boiler-cleaner, a brush having on its upper side a beveled or inclined surface arranged to be acted on by the water as the brush is reciprocated, whereby to force said brush against the surface of the boiler, substantially as set forth.

2. A boiler-cleaner consisting of the brush having a block or body formed on its upper side with a beveled or inclined surface, and a handle connected with said brush, substantially as set forth.

WILLIAM T. HANEY.
